UNITED STATES PATENT OFFICE

2,059,035

TOOTH BRUSH

Sol Rothschild, Brooklyn, N. Y.

Application February 29, 1936, Serial No. 66,372

19 Claims. (Cl. 15—28)

This invention relates in general to toothbrushes and more particularly to a new and improved type of toothbrush, the scrubbing means of which is power driven.

5 A further object of this invention is to provide such a brush that can be used daily without damage to the teeth or the enamel thereon and which can be produced at a cost to come within the means of all.

10 A further object of this invention is to provide such a power driven toothbrush that will thoroughly clean and polish the teeth in a manner not heretofore enjoyed with the conventionally used brush.

15 A further object of this invention is to provide such a power driven toothbrush that will be small and compact so as to fit into the mouth, in substantially the same manner as conventional toothbrushes, without discomfort.

20 Still a further object of this invention is to provide such a power driven toothbrush the scrubbing members of which are removable and replaceable therein.

25 Still a further object of this invention is to provide such a power driven toothbrush with interchangeable means for cleaning or polishing the teeth or for massaging the gums.

30 These together with other objects will now be more particularly described by referring to the following description and claims herein set forth, certain embodiments thereof being illustrated in the accompanying drawing in which:

Figure 1 is a bottom view of the brush with the scrubbing means omitted.

35 Figure 2 is a view of the hinged member which holds the scrubbing means.

Figure 3 is a section taken on the line 1—1 Figure 1 showing the position of the scrubbing means when finally seated.

40 Figure 4 is a side elevational view showing how the scrubbing holding means pivots out of the housing.

Figure 5 is a massage unit of rubber or other material and showing a modified fixing means.

45 Figure 6 is a broken section of a modified arrangement of the holder.

50 Referring to the drawing, 10 is a suitable form of handle which can be constructed to receive a motor 11 which is connected by the cable 12 to an ordinary light socket. Said handle being made of any lightweight suitable material. On the end of the handle is a watertight housing 13, on the bottom of which is arranged a hinged member 14, hinged at 15, which accommodates the 55 scrubbing members.

The motor shaft 16 extends through the handle 10, which is bored at 17 so as to form a watertight bearing for the motor shaft 16, and through the housing 13 where it is journaled in the bearing 18. On the shaft, in the housing, is provided 5 bevel gears 19. The housing, shaft and gears being of rustproof material.

When the hinged member 14 is released by the lock 20, the lock being shown unlocked by dotted lines in Figure 1 and shown locked by solid lines, 10 it is free to be swung to the position as shown in Figure 4. When in this position its rotatable member 14', pivoted at 21, is free to be rotated as shown in Figure 2, thus opening the bearings 22 and 23 formed on the inside of members 14 and 15 14' when the rotatable member is closed and in alignment as shown in Figure 1. It should be noted that such an arrangement makes for quick opening of the housing for various purposes, as for example for quick changing of the scrubbing 20 members as purpose may necessitate. It is obvious other suitable arrangements for opening the housing and bearings may be devised without departing from the invention.

The scrubbing members are preferably made 25 with a disc 24 in which is fixed the bristles or other means 25 and extending from the other side of the disc is a short shank 26 having on its end a bevel gear 27 preferably made with a shoulder 28 thereon. Arrangement of bristles shown 30 is preferred.

When it is desired to insert the scrubbing members in the holder, the hinged member 14 is swung out of the housing, as above described, and its rotatable member 14' rotated so as to 35 open up the bearings 22 and 23 which are designed in length and diameter to accommodate the shanks 26 of the scrubbing members. The scrubbing members are seated in place and the rotatable member 14' is rotated into proper 40 alignment so as to form perfect seating and perfect bearings for the scrubbing members. The hinged member 14 is then pushed back into the housing until it is seated firmly on the rabbet 45 joint 28 formed on the inside walls of the housing 13. In this position the bevel gears 27 on the scrubbing members mesh with the bevel gears 19 on the motor shaft and the lock is pushed over in place to insure against movement of the parts 50 and the brush is ready to operate the instant the current is supplied. The bevel gears 27 on the scrubbing members are shown larger than the bevel gears 19 on the motor shaft thus indicating a slower speed ratio of the scrubbing members 55

with relation to the shaft. It is obvious, however, these gears may be any desirable size or ratio.

Now it should be noted that this invention fully contemplates other arrangements that would give, for instance, reciprocal action circularly, or to and fro action longitudinally and other actions that would move the scrubbing means, but, I prefer the arrangement shown here giving circular action only, which conclusion I came to after exhaustive research, the result indicating that most dentists prefer such circular action for thoroughly cleaning the teeth. This action was particularly recommended for cleaning in between the teeth where most tooth decay usually starts. It is obvious that a single scrubbing member may be used in place of a plurality of scrubbing members, if desired.

It is evident, I am certain, that no tooth brush which is dependent upon the user for results can get such perfect results as my power driven brush, as, most people not only do not give proper time to the brushing of their teeth but almost always use a tooth brush incorrectly. My power driven brush will not only save time but will brush the teeth clean and in the correct manner, namely, with a circular motion such as is recommended by the dental profession.

As a further result of my research, it has come to my attention that if people would massage their gums regularly every day they would be less apt to encounter tooth decay or other tooth ailments as massaging of the gums increases the circulation about the roots of the teeth and makes for healthier teeth. Therefore, this invention fully contemplates such accessories that may be interchangeable with the scrubbing members in my holder for the purpose of massaging the gums, such as members having scrubbing means of rubber, felt or other materials. When materials such as these are employed, especially for massage purposes, it is highly desirable that the scrubbing members be driven at a lower speed than when bristles are employed. This is obviously accomplished by a higher gear ratio of the bevel gears before described. Now with regard to the various scrubbing members just mentioned, it should be noted that the construction of my brush besides providing for the quick changing of the various scrubbing members (without taking the instrument apart) also permits different types of scrubbing members to be held in the holder at the same time, for example, a cleansing and a polishing member or any other desired combination.

In Figure 6 I show a modified arrangement of my holder in which the housing 113 may be made completely sealed. This is made possible by a different arrangement of the scrubbing members, as shown in Figure 5, for instance, wherein the bristles, rubber or other materials 125 are fixed in a separate disc 124, which disc is drilled and tapped at 100. The other parts of the scrubbing members, before described, are now incorporated and fixed in the housing and take the form of a shank 126 having on its inside end a bevel gear 127 and on its outside end a collar 101 and a screw 100'. This part is permanently fixed in the bearing 122, which is made watertight, so that its bevel gear 127 is in mesh with the bevel gear 119 on the shaft 116. When it is desired to use the brush the scrubbing members are fixed in place by means of the tapped bore 100 in the disc 124 engaging in male and female relationship with the screw 100'. The pitch of said bore 100 and screw 100' is naturally made so that the scrubbing

members will not turn off while being rotated and the collars 101 limiting the scrubbing members from becoming too tight.

In order to prevent the turning discs of the scrubbing members from contacting with any part of the mouth while in operation and causing possible injury thereto, I provide an extension wall 30, Figures 1, 3, 4 and 130 Figure 6, which extends just slightly below the rotating discs and thus insures against possible mouth injury.

While the toothbrush illustrated embodies the salient principles of my invention I do not wish to be confined to this arrangement, nor to shapes of its parts, nor to the particular action of the scrubbing members, as it is evident other arrangements and shapes of parts can be devised as well as other actions of the scrubbing members without departing from the scope of my invention as set forth.

Having thus described my invention what I claim as a new article of manufacture is:

1. A tooth brush comprising a handle, rotatable scrubbing members, a motor means in one end of said handle, a housing on the other end of said handle opposite the motor, means in said housing for detachably holding the scrubbing members, said second named means having means therein for holding said scrubbing members in a predetermined fixed position, said second named means being movable for opening and closing same for the insertion therein and the removal therefrom of said scrubbing members, said housing having cooperative means for holding said second named means in predetermined fixed position, and means for engaging said scrubbing members with said motor means whereby the scrubbing means will be rotated.

2. A compact tooth brush comprising, a handle, motor means in said handle, a housing on the end of said handle, a motor shaft extending into said housing and having drive elements thereon connected to said motor means, said housing having an operable member for opening and closing said housing, said member having bearings therein and being operable whereby said bearings may be opened and closed for the quick insertion therein or the quick removal therefrom of scrubbing members, said scrubbing members having means thereon for engaging with the drive elements on the motor shaft whereby the scrubbing members are actuated, and means on said housing for locking said operable member in predetermined fixed position and releasing same therefrom.

3. A compact tooth brush comprising, a handle, motor means in said handle, a housing on the end of said handle, a motor shaft extending into said housing and having drive elements thereon connected to said motor means, said housing having an operable member for opening and closing said housing, said member having bearings therein and being operable whereby said bearings may be opened and closed for the quick insertion therein or the quick removal therefrom of scrubbing members, said scrubbing members comprising scrubbing means fixed in a one piece element which element takes the shape of a plate with the scrubbing means fixed on one side and a shank extending from the other side and having means thereon for engaging with the drive elements on the motor shaft whereby the scrubbing means will be rotated, said housing having means therein for locking said operable member in predetermined fixed position and releasing same therefrom, and said operable member having

means therein for keeping the means on the scrubbing members in engagement with the motor means.

4. A tooth brush comprising a handle, scrubbing members, motor means in one end of said handle, a housing on the other end of said handle opposite the motor, operable means in said housing for holding scrubbing members, said operable means having means therein for holding said scrubbing members in a predetermined fixed position and for permitting the scrubbing members to freely rotate therein, said operable means being movable to and from the housing, said housing having cooperative means therein for holding said operable means in predetermined fixed position so that only a part of the scrubbing members for cleaning will project outside of the housing, and means for engaging said scrubbing members with said motor means whereby the scrubbing means will be rotated.

5. A tooth brush comprising a handle, a motor means in said handle, a drive shaft extending thru said handle and into a housing on the end of said handle, said drive shaft attached to said motor, said housing having an opening for admission thereto, said opening having an operable door attached thereto for opening and closing said opening, said door containing bearings for holding scrubbing members, said bearings being operable to open and close same to permit the insertion therein or the removal therefrom of scrubbing members, said scrubbing members being equipped with drive elements, said shaft having drive mechanisms thereon coacting with said drive elements on said scrubbing members.

6. A tooth brush as described in claim 5 and means forming part of said bearings for holding said drive elements on said scrubbing members in positive engagement with said drive mechanisms on said shaft.

7. A compact tooth brush comprising, a handle, scrubbing members, a motor means in one end of said handle, a housing on the other end of said handle opposite the motor, a motor shaft connected to said motor extending into said housing, means in said housing for holding said scrubbing members, said means being movable into and out of the housing, means forming part of the housing for predeterminedly fixing the position of said last means when moved into said housing, means for locking same in said position, and means for engaging said scrubbing members with said motor shaft whereby the scrubbing members will be actuated.

8. A tooth brush comprising, a handle, scrubbing members, motor means in one end of said handle, a housing on the other end of said handle opposite the motor, a motor shaft connected with said motor means extending into said housing, means in said housing for holding scrubbing members, said means being movable into and out of the housing, means forming part of said housing for predeterminedly fixing the position of said last means when moved into said housing so that only a part of the scrubbing members for cleaning will be exposed from said housing, means for locking same in said position, and means for engaging said scrubbing members with said motor shaft whereby the scrubbing members will be actuated.

9. A tooth brush comprising, a handle, a motor means in said handle, a drive shaft connected therewith, said drive shaft extending through said handle and into a housing on the other end

of said handle opposite the motor means, said housing having an opening, a hinged member for closing said opening, said hinged member having bearings therein, said hinged member comprising operable members movable in relation to each other whereby said bearings may be opened and closed for the insertion therein or the removal therefrom of scrubbing members, said scrubbing members being equipped with drive elements, said drive shaft having drive mechanisms thereon coacting with said drive elements on said scrubbing members, and positive means for holding said drive mechanisms on said shaft in engagement with said drive elements on said scrubbing members.

10. A tooth brush comprising, a handle, a motor means in said handle, a drive shaft connected therewith, said drive shaft extending through said handle and into a housing on the other end of said handle opposite the motor means, said housing having an opening for accommodating a hinged member for closing said opening, said hinged member having bearings therein, said hinged member comprising operable members movable in relation to each other whereby said bearings may be opened and closed for the insertion therein or the removal therefrom of scrubbing members, said scrubbing members being equipped with drive elements, said drive shaft having drive mechanisms thereon coacting with said drive elements on said scrubbing members, and positive means for holding said drive mechanisms on said shaft in engagement with said drive elements on said scrubbing members, and positive means for holding said movable members which are operative for opening and closing the bearings to keep said bearings closed when moved into closed bearing relationship.

11. A tooth brush comprising, a handle, a motor means in said handle, a drive shaft extending through said handle and into a housing on the other end of said handle opposite the motor means, said drive shaft connected with said motor means, said housing having an opening and an operable member for closing same, said operable member having bearings therein, said operable member comprising members movable in relation to each other whereby said bearings may be opened and closed for the insertion therein or the removal therefrom of scrubbing members, positive means for holding said movable members to keep said bearings closed, said scrubbing members being equipped with drive elements, said drive shaft having drive mechanisms thereon coacting with said drive elements on said scrubbing members, and cooperative means forming part of said bearings and said scrubbing members for preventing said drive elements on said scrubbing members from moving out of engagement with the drive mechanisms on said shaft.

12. A tooth brush for the teeth and the like comprising a handle, a motor in said handle, a drive shaft attached to said motor, said shaft extending through said handle and into a housing on one end of said handle, operative bearings forming part of said housing for holding scrubbing members equipped with drive elements, said bearings being operative to permit the insertion therein or the removal therefrom of scrubbing members, and drive mechanisms on said motor shaft adapted to coact with said drive elements on said scrubbing members whereby the scrubbing members will be actuated.

13. A tooth brush comprising, a handle, scrub-

bing members, a motor means in said handle, an operatable means on one end of said handle for holding said scrubbing members, said means being operatable for the insertion therein and the removal therefrom of scrubbing members, drive means on said scrubbing members for engaging with drive mechanisms fixed on a motor shaft connected with said motor means whereby the motor means actuates the scrubbing members, positive means for holding said drive means on said scrubbing members in engagement with the drive mechanisms on said motor shaft, means for locking said operatable means for retaining said scrubbing members therein, and means for holding same in a predetermined fixed position.

14. A tooth brush comprising, a handle, a motor in said handle, a drive shaft extending thru said handle and into a housing on the end of said handle, said drive shaft attached to said motor, said housing having an opening for admission thereinto, said housing having a movable member attached thereto for opening and closing said opening, said movable member containing bearings which are operable to be opened and closed for the insertion therein or the removal therefrom of scrubbing members, said bearings containing means for fixing said scrubbing members in predetermined fixed position therein so that they will be free to rotate therein, said scrubbing members being equipped with drive elements, said shaft having drive mechanisms thereon adapted to coact with said drive elements on said scrubbing members.

15. A tooth brush comprising, a handle, scrubbing members, means on said handle for holding said scrubbing members, said means comprising operable members movable in relation to each other for opening and closing same for the insertion therein and the removal therefrom of said scrubbing members, means forming part of said last means for holding said scrubbing members

in a predetermined fixed position therein, and positive means for actuating said scrubbing members.

16. A tooth brush comprising, a handle, scrubbing members, a housing on said handle, said housing comprising members movable in relation to each other, one of said members comprising means for holding said scrubbing members, said last member being movable towards and away from said housing to open and close said housing, and positive means for actuating said scrubbing members.

17. A tooth brush comprising, a handle, scrubbing members, a housing on said handle, said housing comprising a plurality of parts, said parts being movable in relation to each other, said moving parts comprising means for holding scrubbing members, said means which holds said scrubbing members being adapted to be opened and closed as said movable parts are moved in relation to each other, and positive means for actuating said scrubbing members.

18. A tooth brush comprising, a handle, scrubbing members, a housing on said handle, means connected with said housing for holding scrubbing members therein, said last means comprising a plurality of parts, said parts containing concurring means cooperative with means on said scrubbing members for holding said scrubbing members in a predetermined fixed position in said holding means, and positive means for actuating said scrubbing members.

19. A compact tooth brush comprising, a handle, a scrubbing member, a housing on said handle, said housing having an opening, means for closing said opening, said last means containing means for holding said scrubbing member, said means being movable both toward and away from said housing, and positive means for actuating said scrubbing member.

SOL ROTHSCHILD.
